United States Patent Office.

WATSON SANFORD, OF NEW YORK, N. Y.

Design No. 3,675, dated September 28, 1869.

DESIGN FOR A STOVE.

The Schedule referred to in these Letters Patent and making part of the same.

I, WATSON SANFORD, of the city, county, and State of New York, have invented and produced a new and original Design for a Stove, of which the following is a specification.

The nature of my design is fully represented in the accompanying photographic illustration, to which reference is had.

I claim as my invention—
The design for a stove, as shown.

WATSON SANFORD.
